(57) **CLAIM**

The ornamental design for a deep water crustacean hoop net as shown and described.

DESCRIPTION

FIG. 1 is a perspective view of a first embodiment for a deep water crustacean hoop net of the present design;

FIG. 2 is a left side view thereof;

FIG. 3 is a right side view thereof;

FIG. 4 is a front view thereof;

FIG. 5 is a back view thereof;

FIG. 6 is a top view thereof;

FIG. 7 is a bottom view thereof;

FIG. 8 is a perspective view of a second embodiment for a deep water crustacean hoop net of the present design;

FIG. 9 is a left side view thereof;

FIG. 10 is a right side view thereof;

FIG. 11 is a front view thereof;

FIG. 12 is a back view thereof;

FIG. 13 is a top view thereof; and,

FIG. 14 is a bottom view thereof.

Any shading and cross-hatching are not features of the design but are utilized to illustrate the surface contours of the deep water crustacean hoop net in the drawings. Any broken lines in FIGS. 1 through 14 depict parts of the deep water crustacean hoop net that form no part of the claimed design.

1 Claim, 14 Drawing Sheets
